UNITED STATES PATENT OFFICE

2,579,372

PILOT BURNER

Harold B. Donley, Columbus, Ohio, assignor to
 Columbus Metal Products, Inc., Columbus, Ohio,
 a corporation of Ohio

Application October 11, 1947, Serial No. 779,358

1 Claim. (Cl. 158—91)

1

This invention relates to a pilot burner for use primarily in a burner of the so-called "pot type," and has for one object to provide a pilot burner which may be conveniently positioned within a burner.

Another object is to provide a pilot burner arranged in the line of the main fuel supply for a burner, and so constructed that all of the fuel which is burned within the main burner passes through the pilot burner either to be burned in or near the pilot or to be discharged into the main burner for combustion therein.

Another object is to provide a simple pilot burner for use in a burner and provided with an auxiliary air supply.

Other objects will appear from time to time in the specification and claims.

My invention is illustrated more or less diagrammatically in the accompanying drawings, wherein:

Figure 1 is a vertical section through one form of burner to which the pilot may be applied;

Figure 2 is a sectional detail taken at line 2—2 of Figure 1 illustrating the pilot itself in plan.

Like parts are indicated by like characters in the specification and drawings.

In the form here shown, 1 designates a wall of a burner. The space enclosed by the wall 1 is partially closed by a bottom member 2 which is open as at 3. A ledge member 4 is fixed within the wall 1. A burner pot 5 is positioned within the wall 1 and is supported from the ledge 4 by means of a flange 6 which rests upon the ledge. The pot is closed by a bottom member 7. A flame plate 8 preferably rests upon the flange 6 at the top of the pot. It is provided with an opening 9 and may have an annular centering or positioning member 10 formed in it. The pot 5 is provided with rows or groups of holes 11 and with a final and upwardly positioned row or group of perforations 12. As shown in Figure 1, these are upwardly inclined.

Fuel is supplied to the main burner through a conduit 13 threaded in a nipple 14 which is itself fixed in the wall of the pot 5.

15 indicates generally a pilot housing member. It is open on its bottom and rests against the bottom 7 of the pot, which thus serves as a closure for the pilot housing and assembly. One or more notches or openings 16 are formed in or near the bottom of the pilot member 15, and serve as outlets for fuel not burned or vaporized in the pilot itself.

The pilot housing 15 may be provided with an upwardly directed chimney-like member 17

which defines an outlet opening 18. A wall member 19 formed within, and preferably integral with the pilot housing 15, provides a passage 20 which is closed by the wall 5 of the pot against which the pilot structure is positioned. One or more rows or groups of perforations 21 and 22 may be formed in the wall 19. An upward extension 23 is formed preferably integrally with the pilot housing 15. It is in communication with the air conduit 24 which is threaded into a nipple 25 fixed in the wall 5 of the pot. The extension 23 may include integral members 26 perforated to permit the passage therethrough of bolts or screws 27 or any other means by which the pilot housing and assembly are held in place.

It will be realized that although I have illustrated and described an operative device, still many changes may be made without departing materially from the spirit of my invention, and I wish, therefore, that my showing be taken as in a broad sense illustrative and diagrammatic rather than limiting me to my precise showing.

The use and operation of the invention are as follows:

In the form here shown the device is assembled in an annular pot. It is not limited to that association, and the pot or burner might be of any shape. Whatever the shape of the pot or burner, since it in effect forms one or more walls of the pilot structure, the latter will be given a shape suitable so that it will always fit against one or more walls of the burner in the manner necessary to accomplish satisfactory use.

Fuel both for pilot combustion and for the main combustion enters the conduit 13 from any suitable source. Its quantity may be controlled manually or automatically. Unless burned or vaporized within the pilot structure, fuel is discharged through the opening or openings 16 and flows out onto the floor 1. It is there partially vaporized and a rich mixture rises past the perforations 11 through which air enters. The final or secondary air enters through the perforations 12. Combustion takes place generally above the bottom of the pot toward the upper part of the top, and the flames are formed therein and extend through the opening 9 in the flame plate or ring 8.

When the entire burner is not to be used, and when only the pilot is to be used, the quantity of fuel entering through the conduit 13 is reduced to the point at which it can all be consumed in or adjacent to the pilot, and the following operation takes place. As this limited

quantity of fuel enters through the conduit 13 and passes into the space bounded by the pilot housing 15, the wall 19 and the member 7, some vaporization occurs. Air enters either through the openings 21 or the openings 22 or both in case both are present. This air for accomplishing vaporization and burning of the pilot is supplied through the conduit 24. Pilot combustion occurs at or near the top of the member 17. The pilot flame will generally extend upwardly through the opening 18 and above the upper edge of the member 17. So long as the quantity of fuel which enters the pipe 13 is only sufficient to support combustion at the pilot, the fuel will be entirely burned at or near the upper portion of the pilot, and thus a pilot flame of small size will be maintained economically. When the pilot flame is burning and it is desired to light the entire burner, the quantity of fuel which is discharged through the conduit 13 is increased beyond that which can be burned or vaporized by the pilot. This excess quantity of fuel then flows through the opening or openings 16 into the main burner space. It is there mixed with the air within that space and with the air which enters through the openings 11 and 12, and the main combustion above described occurs. This will be maintained as long as a sufficient quantity of fuel is furnished to maintain it. When the quantity of fuel is again reduced below that necessary to maintain the main combustion, the combustion within and about the pilot continues and will do so until the quantity of fuel is again increased.

I claim:

For use in a burner having a pot which includes a bottom wall and a side wall, a generally imperforate walled pilot structure adapted, when positioned within such a pot, to contact the bottom and side walls of the pot, the pilot structure including generally imperforate top and side

wall portions adapted to define, when abutting the bottom and side walls of a pot, a mixing chamber adapted to receive a liquid fuel supply delivered to the pot, said pilot structure including upper wall portions adapted to define, with the pot side wall, a plenum chamber superposed over the outer portion of the mixing chamber, the plenum chamber being outwardly open and being thereby adapted, when in position in a pot, to receive an air supply through the side wall of the pot, the pilot structure further including a partition separating the plenum chamber and the mixing chamber, the said partition having therein a plurality of air inlet apertures adapted to direct air jets from the interior of the plenum chamber to the mixing chamber space below the partition and within the pilot structure, the pilot structure having top and side wall portions extending inwardly from the plenum chamber, the top wall portion having therein an upwardly open flame aperture, the inwardly extending side wall portion of the mixing chamber being formed to provide a fuel outlet adapted, when the pilot structure is in position in a pot, to permit liquid fuel to flow from the mixing chamber into the interior of the pot.

HAROLD B. DONLEY.
